(57) **CLAIM**

The ornamental design for the digital audio disk player for automobile, as shown and described.

DESCRIPTION

FIG. 1 is a perspective view;

FIG. 2 is a front view;

FIG. 3 is a rear view;

FIG. 4 is a left side view;

FIG. 5 is a right side view;

FIG. 6 is a top plan view; and,

FIG. 7 is a bottom plan view.

The broken lines shown are included for the purpose of illustrating the unclaimed portions of the article and form no part of the claimed design. The lines consisting of long lines and dots indicate conceptual border lines between the claimed portions and the disclaimed portions.
